LOCKING FASTENER

Winthrop F. Ashworth, Wenham, Mass., assignor to United-Carr Fastener Corporation, Cambridge, Mass., a corporation of Delaware

Filed Dec. 29, 1958, Ser. No. 783,479

2 Claims. (Cl. 292—317)

This invention relates to a locking fastener which can be used with a strap or the like.

It is an object of the invention to provide a locking fastener which cannot be opened without leaving visible evidence that it has been opened.

A further object of the invention is to provide a locking fastener which utilizes a fragile plastic plug to lock the fastener.

Other objects of the invention will, in part, be obvious, and will, in part, appear hereinafter.

In the drawings:

Fig. 1 is a top plan view of the top part;

Fig. 2 is a view in side elevation of the top of Fig. 1;

Fig. 3 is a front elevation of the top of Fig. 1;

Fig. 4 is a top plan view of the bottom part;

Fig. 5 is a side elevation of the bottom part of Fig. 4;

Fig. 6 is a front elevation of the bottom part of Fig. 4;

Fig. 7 is a top plan view of the plastic lock;

Fig. 8 is a side elevation of the plastic lock;

Fig. 9 is a top plan view of the plastic lock partly broken away to show locking feature;

Fig. 10 is a view in section taken on line 10—10 of Fig. 9;

Fig. 11 is a bottom plan view of another embodiment;

Fig. 12 is a side elevation of Fig. 11;

Fig. 13 is a side elevation of Fig. 11;

Fig. 14 is an end elevation of Fig. 11;

Fig. 15 is a top plan view of the plastic lock;

Fig. 16 is a side elevation of the plastic lock;

Fig. 17 is a top plan view of the hasp;

Fig. 18 is a top plan view of the hasp, staple and plug engaged and attached to a strap; and

Fig. 19 is a view in section taken on line 19—19 of Fig. 18.

One embodiment of the fastener is illustrated in Figs. 1—10. The fastener comprises a plug receptacle 10, a plug receptacle cover 12, a hinge element 14, and a plug 16. The plug receptacle 10 is formed from one piece of material, in the present instance, aluminum. Naturally any semi-rigid material may be used, such as plastic or most of the metals. The receptacle 10 comprises a base 18, two side walls 20 in integral right angle relationship with said base 18 and in spaced parallel relationship with each other, and a rear wall 22 in integral right angle relationship with said base 18 and also with both side walls 20 as shown in Fig. 4. The base 18 has an attaching means 24 centrally located for attaching the receptacle 10 to a strap 26 or the like. In this embodiment of the invention applicant has drawn a stud attaching means 24 integral with the base 18. Many different types of attaching means 24 could be used for the purpose such as a stud and socket, or eyelet etc. A tongue 21 may be formed integral with the terminal end of the base 18 farthest from the rear wall 22 and extending below the said base 18 in a direction away from the direction of the side walls 20, which on engagement with the strap 26, could be bent toward the base 18 to hold the said strap 26 between the base and the said tongue 21 as

an additional holding means in cooperation with the attaching means 24. The two side walls 20 have a leading edge 28 located at the point farthest from the rear wall 22 and between each of the said leading edges 28 and the rear wall 22, two tabs 30 are formed, one integral with each wall, in right angle relationship with their respective wall 20, in spaced parallel relationship with the base 18 and pointing toward each other as shown in Fig. 4. A rectangular latch 32 is formed integral on one side with the base 18, in acute angular relationship thereto and protruding upward a predetermined distance between the walls 20. The latch 32 may also be triangular or circular in shape.

The said plug receptacle cover 12 comprises a substantially rectangular cap 34, a fore wall 36, an after wall 38, and a flank wall 40. All three of said walls are in integral right angle relationship with said cap 34 and the fore wall 36 and the after wall 38 are in spaced parallel relationship with each other and in right angle relationship with said flank wall 40. The fore wall 36 has an aperture 42 formed therein and has a height from the cap 34 equal to the height of the after wall 38 plus the height of the rear wall 22 of the plug receptacle 10. A connector portion 44 is formed integral with the plug receptacle cover 12 to engage the hinge element 14. In the preferred embodiment the connector portion 44 comprises a flat contiguous element 46 and a cylindrical connector element 48. The hinge element 14 in the preferred embodiment is a rectangular frame in which one of the longer bars 50 is moveably attached to a terminal end 52 of the strap 26. This attachment may be made by looping the said end 52 around the bar 50 and then attaching it to the strap 26 in the usual manner. The other bar 54 is in spaced parallel relationship with its opposite bar 50, is placed axially in the cylindrical connector element 48 so that the receptacle cover 12 can rotate about the bar 54 from the point where it contacts one side of the strap 26 to the opposite side of the strap 26. To engage the receptacle 10 with the receptacle 25 cover 12, the terminal end of the strap 26 on the opposite end from the terminal end 52 is passed through the aperture 56 formed by the frame of the hinge element 14 to allow the cover 12 to be dropped over the receptacle 10 with the fore wall 36 of the cover 12 in contact with the side walls 20 and in spaced parallel relationship with the rear wall 22 of the receptacle 10. The one piece 30 plug 16 is formed of a fragile material, such as plastic in the shape of the capital letter D as shown in Fig. 7. The plug comprises a plug base 58, flexible legs 60 in integral right angle relationship with said base 58 and connected at their ends farthest from the base 58 by an arcuate connecting portion 52 split on the midline of the arc as shown in Fig. 7. The plug 16 is made from plastic or some other material that is easily broken under 35 shear stresses. To engage the receptacle 10, the receptacle cover 12 and the plug 16, the receptacle 10 and the receptacle cover are engaged with each other as herein set forth. The plug 16 is then passed between the walls of the aperture 42 formed in the cover 12 and 40 between the base 18 and the two tabs 30 until the terminal end 52 of the plug 16 passes over the rectangular latch 32 of the plug receptacle. At this point, the plug base 58 abuts the fore wall 36 of the plug receptacle 10 and the plug 16 cannot be withdrawn because the latch 32 holds the plug 16. The receptacle 10 is now engaged with the receptacle cover 12 and the two elements cannot be separated without breaking the plug 16.

A second embodiment of the invention is shown in Figs. 11—19 wherein an ordinary hasp 64 and staple 66 are used as two of the three basic elements of the invention. Engaged with the hasp 64 is the third element, a plug receptacle 68. The plug receptacle 68 comprises

a base plate 70 generally rectangular in shape having its two longer side edges bent in right angle relationship to the said base plate 70 to form side walls 72, 73 and said side walls 72 and 73 are in opposed spaced parallel relationship with each other as best illustrated in Fig. 14. An aperture 74 is formed in the base plate 70 approximately midway between the side walls 72 and 73 in the form shown in Fig. 11 similar to the spherical form of the hasp aperture. The tops of the side walls 72 and 73 are bent in right angles to themselves to form wing portions 76. The planes of wing portions 76 are in spaced parallel relationship with the plane of the base plate 70 as shown in Fig. 14. An engagement tab 78 is formed in the side wall 72 so that it protrudes into the area defined by the side wall 72, its wing portion 76 and the base plate 70 as best illustrated in Figs. 11 and 14. On the opposite side of the base plate 70 from that on which the tab 78 is located, a rectangular aperture 80 is formed in the side wall 73, the base plate 70 forming one edge of said aperture 80. The rectangular aperture 80 is formed by shearing two projections 82 from the side wall 72. The projections 82 protrude into the area defined by the base plate 70 and the side walls 72 and 73 as shown in Fig. 11. Each of the projections 82 have terminal contact edges 84. Semi-circular tabs 86 are sheared from the base plate 70 to protrude toward the wing portions 76 as is best shown in Fig. 14. The position of the tabs 86 is best shown in Fig. 11. The tabs 86 are four in number, two on each side of the aperture 74 and lying under the wing portions 76. The distance from one tab 86 to its opposite member tab 86 is always smaller than the width of the hasp 64 as will be more fully explained hereinafter. The semi-circular tabs 86 are integral with the base plate 70. The hasp 64 is basically of a form old in the art having two straight side edges 88, separated by a spherical aperture 90 and connected at one of each of their terminal ends by an integral arcuate portion 92, their opposite terminal ends are connected by a rectangular base edge 93. The base edge 93 is curled about one of the longer arms 94 of a square frame 95, and the opposite longer arm 97 is in spaced parallel relationship with said arm 94 and moveably attached to a leather strap 96 as shown in Figs. 17 and 18. One of the straight side edges 88 of the hasp 64 has formed therein an acute angular notch 98 with its apex pointing toward the base edge 93 as shown in Fig. 17. The design of the notch 98 is not critical as long as it contains an indentation and a stop edge 100 in right angle relationship with the axis of the aperture 90 of the hasp 64. An embossment 102 may be formed about the periphery of the aperture 90 to provide strength although such embossment is not absolutely necessary. To engage the hasp 64 with the plug receptacle 68, the straight side edges 88 of the hasp 64 ride over the arcuate portion of the semi circular tabs 86 and under the wing portions 76. The engagement tab 78 rides on the side edge 88 in which the angular notch 98 is formed. The plug receptacle 68 is pushed onto the hasp 64 until the engagement tab 78 snaps into the notch 98 so that the free terminal end of the engagement tab 78 rests against the stop 100 of the notch 98. The receptacle 68 can now be moved a short distance between the curled portion of the base edge 93 and the stop 100 as determined by the length of the engagement tab 78. In this engaged position the aperture 74 of the plug receptacle 68 is in spaced parallel relationship with the aperture 90 of the hasp 64.

The staple 66 is attached to the strap 96 using any of

the many available attaching methods. The end of the strap 96 is passed between the longer arms 94 of the rectangular frame 95. The staple 66 is of the arcuate form, old in the art, and it is passed between the walls 5 of the apertures 74 and 90 until the wing portions 76 rest against the strap 96. The plug 16a is formed similarly to the plug 16 of the same materials except that two angular notches are formed in the legs of the plug 16a as shown in Fig. 15.

10 To lock the hasp 64, the plug receptacle 68 and the staple 66 together after these three pieces have been engaged as explained herein, the plug 16a is passed between the walls of the rectangular aperture 80 of the plug receptacle 68 until its plug base 58a rests against 15 the side wall 73 as shown in Fig. 18. The projections 82 snap into the notches of the plug 16a preventing its removal from the receptacle 68 without breaking the plug 16a. The bight of the arcuate portion of the plug 16a is made so that when the plug is completely inserted into 20 the plug receptacle, it is superimposed over the aperture 90 of the hasp 64 and lies between the hasp 64 and the plug receptacle base plate 68. In this position it also lies in the area formed by the staple 66. The hasp 64, the receptacle 68 and the staple 66 are now locked together and cannot be separated without breaking the plug 16a. If the device described were used to bind a mail bag together, the bag could not be opened without creating an easily detectable damage to the bag or fastener.

25 30 Since certain other obvious modifications may be made in this device without departing from the scope of the invention, it is intended that all matter contained herein be interpreted in an illustrative and not in a limiting sense.

I claim:

35 1. A locking fastener comprising a plug receptacle, a plug receptacle cover and a plug, said plug receptacle having two side walls in spaced parallel relationship, a base portion in right angle relationship with said side walls, extending the full length of said side walls, and 40 an end wall in right angle relationship with said base portion, said base portion having a latch member sheared therefrom in acute angular relationship thereto, said side walls each having a tab in right angle relationship therewith and in spaced parallel relationship with said base portion, said plug receptacle cover having a rectangular cap, a fore wall and an after wall in spaced parallel relationship with each other and in right angle relationship with said cap, and a flank wall in right angle relationship with said cap, said walls and cap forming a four sided 45 compartment, said fore wall having an aperture formed therein, whereby said plug can be passed between the walls of said aperture in said fore wall, between the base portion and said tabs to engage said latch member, thereby locking the said plug receptacle to the said plug receptacle cover.

50 55 2. A fastener as disclosed in claim 1 wherein the plug comprises an arcuate flexible member and a plug base connecting the terminal ends of said arcuate member.
